RUBBER CAP-WRENCH

John W. Waterhouse, Portland, Oreg., assignor to
George E. Watts, Portland, Oreg.

Application March 16, 1932. Serial No. 599,187

6 Claims. (Cl. 81—3.1)

My invention relates to improvements in rubber cap-wrenches for opening and sealing preserve jars or other containers closed with a screw cap, and more particularly to a unique form 5 thereof providing for a great variety of uses and low manufacturing cost.

The principal object of my invention is the provision in a wrench of the character described of means to convert a portion of the twisting 10 effort exerted upon the device into centripetal forces to render the frictional engagement of the device positive.

A second object is to provide for the increase in diameter of the part of the device held in the 15 hand to that extent necessary to set up tensile strains therein of a magnitude essential to the insurance of unbroken circumferential contact of the device with the cap to which it is applied.

A third object is to provide for increased leverages as the need therefor arises.

A fourth object is to provide for manufacturing and shipping economies.

A fifth object is to provide for an enhanced durability of such devices.

25 Other objects and advantages of my invention are apparent in the following discourse wherein the significance of the reference numerals in the accompanying drawing, details of construction and operation of a typical device embodying my 30 invention, and the particular utility thereof are explained.

Figure 1 represents a view of the obverse side of the entire device.

Figure 2 represents a view of the reverse side 35 of the entire device.

Figure 3 represents a view of the side of the device from which a section has been removed to reveal the features of the inside.

40 Figure 4 is a view of a fragment of a preserve jar with cap attached to which the wrench of my invention has been applied, the same being cut away to reveal certain aspects of the engagement.

Figure 5 is a diagram illustrative of a variant 45 manner of use of the device upon caps of relatively small diameter.

The entire device is of molded rubber and is of 50 annular form. The inside of the device is formed with a series of uniform leaves as 1, extending from one side to the other. These leaves are uniformly inclined from the radial position. As viewed from one side these leaves will be inclined in one direction and when the device is turned over the leaves will be inclined in the 55 opposite direction.

The whole of the device, being made of rubber, will be elastic and flexible in all of its parts.

When the wrench is applied to a preserve jar cap to unscrew the latter, it is applied with the side represented by Figure 1 uppermost. To seal 60 a jar the wrench is applied so that the side represented by Figure 2 is uppermost. It will be observed that the leaves 1 incline in opposite directions.

The wrench is made of such size as will provide 65 a minimum normal diameter between the innermost leaf edges 2 of slightly less than the diameter of the jar cap.

To apply the wrench to unscrew a jar cap it is placed over the cap in the position illustrated in 70 Figure 1 and rotated clockwise as downward pressure is applied with the hand. The leaves will thus be bent or folded together and the wrench will slip readily over the jar cap. When the wrench is in the position illustrated in Figure 4, 75 a counter-clockwise rotation is imparted to unscrew the jar cap. In this direction of rotation, the leaves 1 with the innermost edges 2 thereof in frictional contact with the jar cap 4 will be bent away from each other and then to assume 80 an attitude approaching a true radial disposition. It will be obvious that as the leaves are thus unfolded or bent toward the radial position, the whole wrench will be strained in tension and the leaves themselves compressed between the 85 thus tightly drawn out portion 3 and the jar cap 4.

Several valuable effects will be apparent: a portion of the twisting effort applied by the hand 90 of the user will be converted into centripetal forces tending to increase the friction between the leaf edges 2 and the jar cap 4; the whole wrench will be expanded to a larger diameter thus increasing the leverage; and the body of the wrench 3 will 95 be strained in tension so that any force ordinarily used will not be likely to stretch the wrench to an extent where contact between the leaf edges 2 and the jar cap 4 will be broken.

From the foregoing it will be apparent that the 100 wrench may be used ratchet-wise to either seal or open a preserve jar or turn a cap of any sort to which the wrench may be applied.

In Figure 5 is illustrated a variant use of the wrench as applied to a small bottle cap 6, or water 105 bottle cap, or the like. In this use, the loop 5 formed by bending the wrench around a small cap, is grasped in the hand.

Rubber being of considerable efficiency as a 110 thermal insulator, the device has many uses about

a kitchen or shop where heated objects must be handled.

It is also to be particularly noticed that if the wrench of my invention be used to both seal and open the same containers, the wear on the wrench will be nearly equally divided between the two sides, thus approximately doubling the durability as compared with other wrenches of similar character where the same side of the wrench is employed for both sealing and opening.

Having described my invention what I claim is:

1. A rubber cap-wrench of annular form fashioned on the inside with leaves inclined to the several radii.

15 2. A rubber cap-wrench of annular form fashioned on the inside with a broken cylindrical face the fragments of which are supported upon obliquely projecting leaves.

20

80

3. A rubber cap-wrench of annular form fashioned on the inside with leaves disposed in planes parallel to the axis and inclined to the radii thereof.

4. A rubber cap-wrench of annular form fashioned on the inside with obliquely projecting leaves.

5. A rubber cap-wrench of annular form fashioned on the inside with an interrupted cylindrical surface the fragments of which are supported upon obliquely projecting leaves of greater length than the inward radial extension thereof.

6. A rubber cap-wrench of annular form fashioned on the inside with oblique leaves disposed in planes respectively tangent to a relatively smaller but concentric cylinder.

JOHN W. WATERHOUSE.
